PHOTO-ELECTRIC APPARATUS

Filed August 22, 1925

Inventor;
Russell Hart,
per Arthur J. Farnsworth,
Attorney.

UNITED STATES PATENT OFFICE.

RUSSELL HART, OF LOS ANGELES, CALIFORNIA.

PHOTO-ELECTRIC APPARATUS.

Application filed August 22, 1925. Serial No. 51,850.

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects 10 and advantages, other than those specifically mentioned, are included within its scope.

My invention relates to means for photographically recording variations in a modulated electric current, and it is applicable to 15 such uses as the photographic recording of sound waves and for tele-photographic receiving. Its principal objects include: first, to provide an apparatus that is specially adapted for this general purpose and which 20 is exceedingly sensitive, and responsive to the most minute variations in an electric current; second, to supply facilities for recording electric modulations in either of two distinct ways viz, by means of a record of substantially uniform width and varying density, and by means of a record of varying width and substantially uniform density; third, to make it possible to produce a very sharply defined record of either of the above 25 types upon a photographic film, while running at the standard speed employed in the motion picture art; and, fourth, to accomplish all of the foregoing objects in a single apparatus of relatively great simplicity and small cost.

My objects are attained by means of the apparatus illustrated in the accompanying drawing, in which—

Figure 1 is a plan view of the entire recording portion of my apparatus;

Figure 2 is an enlarged elevation, shown partly in section, of an approved light modulating means;

Figure 3 is an enlarged elevation of the 45 cylindrical mirror I employ in connection with my apparatus, and the means whereby it may be adjusted to allow of producing either of the types of record described above;

Figure 4 is an elevation of the type of primary light source I prefer to employ;

Figure 5 is a plan view of a fragment of motion picture film with a sound record thereon of the varying density type; and

Figure 6 is a plan view of a similar film 55 with a sound record of uniform density and variable width.

Similar reference numerals refer to similar parts throughout the several views.

In previous applications for United States patents I have illustrated and described means for producing similar sound records, and for reproducing sound therefrom. I have not hitherto shown or described, however, the specific means illustrated and claimed herein.

Before passing to a detailed description of my present invention it is to be noted that the standard speed of motion picture film is about one foot per second; and that the frequency of the modulations it may be desired to record is often as high as 5000 cycles per second. Consequently the successive "peaks" of the record may be only about two thousandths of an inch apart. Such a record must be exceedingly sharp and clearly defined to allow of reproduction without blurring or distortion. Any such effect as overlapping of successive "peaks" is fatal to satisfactory reproduction.

In the embodiment of my invention selected for illustrative purposes, I employ for the primary light source a tubular lamp 7, having a reasonably rugged rectilinear filament 8 therein. This filament is mounted under tension between resilient terminals 9, in such manner that the filament will remain under tension when heated, and thus be able to maintain its rectilinearity.

The rays 10 from the incandescent filament are permitted to fall upon a small cylindrical mirror 11, and to be reflected thereby through a focusing lens system 12, upon a photographic film 13. The effect of attenuation of an image produced by a cylindrical mirror is well known, and this effect varies inversely to the radius of the mirror. If, therefore, the filament 8 is say 1/100 of an inch in diameter, the reflected image of the filament may easily be made 1/1000 of an inch in width by employing a sufficiently small radius for the mirror. A secondary image of the above primary image is focused upon film 13 by lens system 12, and the secondary image can easily be made still more tenuous by means of the lens. In this manner it is possible to throw an exceedingly narrow band of light upon the film for exposure purposes.

While being exposed, the film 13 is moved at a uniform speed by means of sprocket drum 14, and it is held in contact with the drum by means of its tension and the assist-

ance of guide rollers 15. The film is housed within a light-tight box of which a portion of the wall is indicated in section at 16.

For modulating the film exposure I may 5 use various types of electro-magnetic devices for variably intercepting the light rays from the filament before they fall upon the mirror. A preferred type of apparatus for this purpose is indicated at 17, and its construction 10 and functioning will be best understood by considering Figures 1 and 2, and especially the latter.

This illustrated ray interceptor comprises an electro-magnet having an exciting coil 18,

15 a circularly bored pole 19, and a cylindrical pole 20 within the bored pole. This device is mounted upon a base 21 of non-magnetic material. Within the tubular gap between the two poles is the modulating coil 22 wound upon a floating tubular shell 23. This shell is mounted upon a light four-armed spider 24 which, in turn, is supported by a thin strip 25 of resilient material attached to the outer face of pole 19. The 20 spider is attached to the strip by means of a screw 26, and the latter carries a knife-edged target 27 at its outer end. Coil 22 is connected by its leads 28 in the circuit whose modulations it is desired to record, and the 25 variations in the current will cause target 27 to vibrate in its own plane in consonance therewith. I usually find it desirable to mount the strip 25 between washers of fibrous material such as paper, as shown at 29; and usually also I employ pieces of sponge 30 rubber 30, crowded between this strip and the fingers 31, to damp the vibrations of the strip. I have found that sheet aluminum is a satisfactory material of which to make 35 strip 25.

The interceptor is set upon base 21 with knife edge 32 of its target in the path of rays 10, and as close as possible to mirror 11, the plane of the target being perpendicular to the rays. The vibrations of the target 40 will thus cause the rays to be variably intercepted, and thereby vary the exposure of film 13.

It is important that target 27 should be 45 positioned as described since the greatest result is obtained in this manner. When so positioned a vibration of even minute amplitude will produce a noticeable variation in the exposure of the film. This makes it 50 possible to record the slightest variations in the modulated current in true and undistorted relation as to both frequency and amplitude.

For producing the type of record illustrated at 33, the axis of mirror 11 is made 60 parallel to knife-edge 32. Vibration of the target in this case causes a corresponding variation in the width of the primary image reflected from the mirror, the length of the 65 image remaining constant. The resulting ex-

posure of the film will be a band of uniform width and greatly varying density.

For producing the type of record shown at 34, the mirror is adjusted so that its axis is slightly out of parallelism with knife-edge 32. In this case also the vibrations of the target result in partially eclipsing rays 10, but the effect upon the primary image is to vary its visible length without materially altering its width. The rapid 70 and constant changes in the length of the image produces a record of uniform density with a sharply serrated edge.

The adjustment of the mirror is effected by angularly and longitudinally positioning 80 its supporting bar 35, and is maintained by set screw 36.

In all apparatus designed to accomplish the purposes of this invention, the greatest difficulties have been: to secure the requisite 85 degree of fineness of the record; to prevent overlapping of the succeeding modulations; and to obtain freedom from the effects of such outside influences as vibration, temperature changes, and distortion due to electro-magnetic and electro-static fields. The apparatus described is capable of overcoming 90 all these difficulties in a high degree, and by its use I have succeeded repeatedly in producing eminently satisfactory sound records. 95 Such records when properly used have given the most faithful of reproductions and are particularly notable for intonation, clear articulation, and quality of tone.

The preceding description has suggested 100 the use of this invention for recording sound for reproduction. For this purpose a current is telephonically modulated and made to pass through coil 22. Obviously records can be made in a similar manner when the 105 current in coil 22 is photo-modulated. The invention is thus adapted for the purposes of telephotography. For the latter purpose supplementary means must be provided for imparting a lateral movement to the film to 110 accomplish scanning. Various scanning means have already been developed and are known to those familiar with the art concerned. Such means do not constitute a part 115 of the present invention and are not claimed herein.

I claim:—

1. Apparatus of the character described, comprising; a rectilinear light source; a uniformly movable photo-sensitized surface; a cylindrical mirror whereby an image of said source may be reflected upon said surface; and means for variably eclipsing rays from said source to modify the proportions of the reflected image to correspond to modulations 120 of current in an electric circuit.

2. Apparatus of the character described, comprising; a rectilinear light source; a uniformly movable photo-sensitized surface; a cylindrical mirror whereby an attenuated 125

image of said source may be reflected upon said surface transversely to its direction of motion; and means for variably eclipsing rays from said source to modify the area of 5 the reflected image to correspond to modulations of current in an electric circuit

3. Apparatus of the character described, comprising; an illuminable rectilinear filament; a uniformly movable photo-sensitized 10 surface; a cylindrical mirror whereby an attenuated image of said filament may be reflected upon said surface transversely to its direction of motion; and a target vibratile to modulations of current in an electric circuit, whereby radiations from said filament 15 may be variably eclipsed between the filament and mirror to modify the proportions of said reflected image.

4. Apparatus of the character described, 20 comprising; an illuminable rectilinear filament; a uniformly movable photo-sensitized surface; a cylindrical mirror of small radius, whereby a much attenuated image of said filament may be reflected upon said surface 25 transversely to its direction of motion; and a sharp-edged target adjacent the mirror and vibratile to modulations of current in an electric circuit, whereby radiations from said filament may be variably eclipsed between 30 the filament and mirror to modify the area of said reflected image.

5. Apparatus of the character described, comprising; an illuminable rectilinear filament; a uniformly movable photo-sensitized 35 surface; a cylindrical mirror of small radius, whereby a much attenuated image of said filament may be reflected upon said surface transversely to its direction of motion; and a sharp-edged target adjacent the mirror and vibratile in its own plane to modulations of current in an electric circuit, whereby radiations from said filament may be variably eclipsed between the filament and mirror, to modify the area of said reflected 40 image in proportion to said modulations. 45

6. Apparatus of the character described, comprising; an illuminable rectilinear filament; a uniformly movable photo-sensitized surface; a cylindrical mirror of small radius, whereby a much attenuated image of said 50 filament may be reflected upon said surface transversely to its direction of motion; a lens intermediate said mirror and said surface; and a target adjacent the mirror and vibratile in its own plane to modulations of current in an electric circuit; said target being intermediate said filament and said mirror, and having a sharp edge whereby radiations from the filament may be variably 55 eclipsed to modify the area of said reflected image in proportion to said modulations. 60
